UNITED STATES PATENT OFFICE

169,848

BRASSIÈRE

Léon Josephson, Paris, France

Application November 18, 1952, Serial No. 22,363
In Great Britain September 13, 1952

Term of patent 14 years

(Cl. D20—4)

To all whom it may concern:

Be it known that I, Léon Josephson, a citizen of the Republic of France, residing at 185 rue de Courcelles, Paris, France, have invented a new, original, and ornamental Design for a Brassière, of which the following is a specification, reference being had to the accompanying drawing, forming part hereof, in which:

Fig. 1 is a front view of a brassière, showing my new design; and

Fig. 2 is a rear view thereof.

I claim:

The ornamental design for a brassière, as shown.

LÉON JOSEPHSON.
